United States Patent Office.

JOHN L. MCINTOSH, OF BOSTON, MASSACHUSETTS, ASSIGNOR TO HIMSELF,
JAMES BLENKINSOP, AND WILLIAM H. VAUGHN.

Letters Patent No. 82,335, dated September 22, 1868; antedated September 7, 1868.

IMPROVED PINKING-TOOL.

The Schedule referred to in these Letters Patent and making part of the same.

TO ALL WHOM IT MAY CONCERN:

Be it known that I, JOHN L. MCINTOSH, of Boston, in the county of Suffolk, and State of Massachusetts, have invented a new and improved Pinking-Machine and Button-Hole Cutter; and I do hereby declare that the following is a full, and exact description of the same, reference being had to the accompanying drawings, with letters of reference marked thereon.

The nature of my invention is a combination of a pair of pincers, or scissors-handles, with a pinking-tool; also with a button-hole cutter, and gauge for the same, and a cutting-block, for the purpose of cutting the edges of cloth, leather, &c., into various shapes, and of cutting button-holes.

In the drawings annexed—

Figure 1 is a side view of my invention

Figure 2 is a vertical section of the cutting-part of the machine.

Figures 3 and 4 are respectively a side view and an end view of two pinking-tools.

And in the drawings annexed, A A, fig. 1, are the lower handle and upper jaw, and B B, fig. 1, are the upper handle and lower jaw of a metallic device of two levers, connected by and playing upon the rivet C, fig. 1, and resembling a pair of pincers. D is a spring, firmly fastened, by the screw or rivet E, to the inside of the lower handle, and playing loosely upon the opposite handle. The upper jaw contains, in its lower side, a socket at F, fig. 1, (dotted lines,) and bears, at right angles to the socket, a thumb-screw, G, called the "tool-screw." In this socket fits the shank of the pinking-tool, which tool differs in no respect from an ordinary pinking-tool, except that it has a shorter handle. The lower jaw B bears in the socket seen in figs. 1 and 2, the flat round block H, figs. 1 and 2, of brass, soft metal, wood, hardened rubber, or other substance, called the "cutting-block." This block is held to the jaw by the set-screws I, figs. 1 and 2, called the "block-screw." This screw passes through an aperture bored perpendicularly through the bottom of the lower jaw B, which aperture is made of greater diameter than the screw. J, figs. 1 and 2, is a piece of rubber, for which I sometimes substitute any other elastic substance, lying between the cutter-block H and its support. K, fig. 1, is a gauge, sliding back and forth upon the side of the handle B, guided by the pin L, fig. 1, which works in the slot seen in the gauge, and is held in place by the set-screw M, fig. 1, called the "gauge set-screw." N, fig. 1, is a tool for cutting button-holes, being a hollow truncated cone of steel, with its narrower and lower end sharpened, and bearing attached to its side a flat piece of steel, also sharpened at its lower end, and bearing a tang or handle at its top. O is a representation of the face of this button-hole tool. P P are pinking-tools, made in the ordinary fashion, but with shorter handles, and below them are representations of their faces.

And the operation of my device is this: I place in the upper jaw a pinking-tool, bearing the device or figure to which I wish to bring the substance operated on, and secure it there by the tool-screw. Then, placing the edge of a piece of cloth upon the cutting-block, I press the two levers or handles together, and bring down the pinking-tool upon it. I find that there is not entire parallelism between the two meeting-portions of the device. Pressing it more strongly, however, the India-rubber spring J gives way, and the surface of the cutting-block accommodates itself to the edge of the pinking-tool, the enlargement of the aperture through which the lower part of the block-screw runs permitting the adjustment. The cloth or other substance operated on is thus readily and clearly cut, when, withdrawing it, another portion of the cloth is submitted to the action of the tool, and the process proceeds. In the intervals of using the tool, I rotate the cutting-block upon the block-screw I, thus preventing continued action of the sharp edge of the pinking-iron or other tool making a corresponding channel upon the face of the cutting-block.

And when I desire to cut button-holes, I remove the pinking-tool, and replace it with the tool represented. Then arranging my gauge, so that the proposed button-hole may be at a proper distance from the edge of the cloth, I proceed to cut the holes. And I sometimes have but one lever, the upper one, and join it to the upper jaw. And I sometimes dispense with the screw to hold the cutting-block, and keep it in place with a flange or a spring.

And what I claim herein as my own invention, and desire to secure by Letters Patent, is—

A machine or device for pinking leather, cloth, &c., consisting of a lever, armed at one end with a tool and a tool-bearing socket, (the latter so arranged as that the pinking-tool may be changed at pleasure,) in combination with the revolving block, when the same is supported and made adjustable by a spring beneath, all substantially as and for the purpose described.

J. L. McINTOSH.
